Specification for Design.

Patented Dec. 5, 1916.

Application filed June 9, 1916. Serial No. 102,789. Term of patent 7 years.

To all whom it may concern:

Be it known that I, HENRY G. CORDLEY, a citizen of the United States, residing at Glen Ridge, in the county of Essex and State of New Jersey, have invented a new, original, and ornamental Design for Liquid-Dispensers, of which the following is a specification, reference being had to the accompanying drawing, forming a part thereof.

The figure is a perspective view of a liquid dispenser showing my new design.

In order to indicate the use of a faucet with my dispenser, without implying any limitations by its contour or position, for it forms no part of the invention, a faucet is indicated in dotted lines. In dotted lines is shown a bottle with which the dispenser of my invention may be used, but which forms no part of the invention.

I claim:

The ornamental design for a liquid dispenser as shown and described.

In testimony whereof, I have signed my name to this specification in the presence of two subscribing witnesses.

HENRY G. CORDLEY.
